(57) **CLAIM**

The ornamental design for my sheathed spring for strain relief of consumer electronics cords, as shown and described herein.

DESCRIPTION

FIG. 1 is a front and side perspective view of a sheathed spring for strain relief of consumer electronics cords, shown in 2 different use conditions;

FIG. 2 is a front view thereof;

FIG. 3 is a back view thereof;

FIG. 4 is a top view thereof with the bottom view being a mirror image thereof; and,

FIG. 5 is a left side view thereof with the right side view being a mirror image thereof.

The dotted lines of FIG. 1 illustrate environmental conditions only and form no part of the claimed design.
